UNITED STATES PATENT OFFICE.

SETH DUNN, OF MONTICELLO, UTAH, ASSIGNOR OF TWO-THIRDS TO ULYSSES G. MERRILL AND WILLIAM S. MERRILL, OF SAME PLACE.

AMALGAMATOR.

SPECIFICATION forming part of Letters Patent No. 555,762, dated March 3, 1896.

Application filed May 15, 1895. Serial No. 549,416. (No model.)

To all whom it may concern:

Be it known that I, SETH DUNN, of Monticello, in the county of San Juan and Territory of Utah, have invented a new and Improved 5 Amalgamator, of which the following is a full, clear, and exact description.

The object of the invention is to provide a new and improved amalgamator which is simple and durable in construction, very effective 10 in operation, and more especially designed for placer mining and milling amalgamation of free-milling ores.

The invention consists principally of a riffle-frame arranged to swing and extending in an 15 inclined downward direction, and means for imparting a shaking motion to the said frame.

The invention also consists of certain parts and details and combinations of the same, as will be fully described hereinafter and then 20 pointed out in the claims.

Reference is to be had to the accompanying drawings, forming a part of this specification, in which similar letters of reference indicate 25 corresponding parts in all the figures.

Figure 1 is a plan view of the improvement with parts broken out. Fig. 2 is a sectional side elevation of the same on the line 2 2 of Fig. 1. Fig. 3 is a cross-section of the same on the line 3 3 of Fig. 2, and Fig. 4 is a sectional plan view of part of the improvement 30 on the line 4 4 of Fig. 2.

The improved amalgamator is provided with a suitably-constructed frame A, in one end of which is arranged a hopper B, having 35 a hinged cover or lid B', adapted to be swung open, as indicated in Figs. 1 and 2.

The frame A is made in the form of a casting designed to be entirely closed at its top and rear end when the machine is in operation, but in order to reach the interior for the purpose of removing the amalgamated gold and to reach the working parts for the purpose of cleaning or repairing the top cover is hinged to one of the side pieces and the 45 rear end is made in the form of a hinged door.

In the hopper B and its cover B' is mounted to turn a water-wheel C, having the usual buckets and deriving its supply of water and gold-bearing sand to be amalgamated through 50 a suitable chute connected with the top of the cover B'. The wheel C is thus rotated by the

force of the water and sand passing through the wheel, and the water and sand are delivered in measured quantities upon a downwardly-extending chute D, arranged under 55 the open bottom of the hopper B and extending a suitable distance downward in the frame A, to finally discharge upon a second chute E, inclined downwardly from the top of the frame A, but in an opposite direction to the 60 inclination of the chute D.

The lower end of the chute E discharges upon the head of a riffle-frame F, provided with transversely-extending riffles F' and hung on links H and H', pivoted at their upper 65 ends to the frame A, as indicated in the drawings. The riffle-frame F extends in a downward direction, and the riffles consist of a series of parallel corrugations arranged closely together and transversely rounded, so that the 70 water and sand will not be greatly retarded and so that upon imparting a shaking motion to the riffle-frame the gold settles in the quicksilver contained in the bottom between adjacent riffles, while the sand and water passes 75 over the riffles, to be finally discharged at the lower end of the frame.

The riffle-frame F receives its shaking motion from the water-wheel C, and for this purpose one of the links H is provided with a pin 80 H², extending through an elongated slot I' in a link I, pivotally connected with an arm J, extending from a shaft J', mounted to turn in suitable bearings in the sides of the frame A. An arm J² is secured on the shaft J' and 85 forms with the arm J a bell-crank lever, and this arm J² is connected by a link K with an arm L, attached to the shaft C' of the water-wheel C. Thus when the wheel is rotated by the force of the water and sand passing 90 through the wheel C, the said wheel imparts a swinging motion to the riffle-frame F, whereby the gold-bearing sand is agitated in the manner previously described. Thus it will be seen that the water-wheel C has a double 95 function, by first delivering a measured quantity of water and sand to the chute D and finally by the chute E to the riffle-frame F, and, secondly, the riffle-frame receives a swinging motion from the said water-wheel 100 by the mechanism above described.

Having thus fully described my invention,

I claim as new and desire to secure by Letters Patent—

1. An amalgamator comprising a frame made in the form of a casing having a hinged 5 top and a hinged rear end, a hopper on one end of said frame having a cover provided with a chute, a feed-wheel in said hopper oppositely-inclined chutes for receiving material from the hopper, a riffle-frame adapted 10 to swing, and mechanism having connection with the feed-wheel for moving the riffle-frame, substantially as specified.
2. An amalgamator comprising an inclined frame having a hopper at its upper end, the 15 said hopper comprising a cover having a chute

for the entrance of material, a bucket-wheel in said hopper adapted to deliver material in measured quantities, an inclined chute receiving material from the wheel, another chute for receiving material from the first-named 20 chute and inclined in an opposite direction thereto, a riffle-frame, connections between the riffle-frame and the wheel whereby shaking motion is imparted to the frame from the wheel and riffles in the frame, substantially 25 as specified.

SETH DUNN.
